COMBINATION STOOL

Leona Michaelis and Edward Michaelis,
Clifton Heights, Pa.

Application November 7, 1950, Serial No. 194,405

6 Claims. (Cl. 228—16)

1

The present invention relates to kitchen stools generally and is concerned primarily with a kitchen stool which is designed to function not only as a stool but also as a carrier and storage receptacle.

In accordance with the modern trend of home design, space in the kitchen is becoming more and more restricted. Present day apartments are ordinarily designed with only a limited amount of kitchen space and this is equally true of the average dwelling house. In such small quarters it is highly desirable to utilize to as great an extent as possible every bit of available space, and the present invention is founded on this belief as its motivating cause.

The invention has in view as its foremost objective the provision of a kitchen stool which is so designed and constructed as to be applicable to other uses in the kitchen and throughout the home.

Somewhat more in detail the invention has as an object the provision of a kitchen stool which includes a closed-in receptacle that is adapted for use for storage purposes. The storage space is located immediately beneath the seat of the stool and access thereto may be had by hingedly mounting the seat in the stool whereby it functions as a closure.

As a corollary to this object, a further object is to provide, in a kitchen stool of the type indicated, a storage receptacle having an auxiliary closure located at the side. With such an auxiliary closure, access may be had to the storage space without disturbing an occupant of the stool.

Still another highly important object of the invention is to provide, in a kitchen stool of the type indicated, a supporting leg structure including rear legs which are mounted on wheels, rollers or comparable devices, whereby the stool is rendered mobile.

Following this objective, the kitchen stool is provided with a back rest which is also adapted for use as a handle when the stool is being moved about from place to place. This back rest, together with the wheels at the lower ends of the rear legs, enable the stool to be used much in the manner of a wheelbarrow or two-wheel pushcart, with the space ordinarily used for storage purposes accommodating the materials which are to be moved.

Yet another object of the invention is to provide, in a kitchen stool of the character aforesaid, front leg structure including step elements which cooperate to provide what is in effect a short

2

step ladder. The leg structure is so designed as to afford the necessary stability when the stool is used as a step ladder, and the mobile character of the stool facilitates such use in that the stool may be moved about to any place where a step ladder is required.

Various other more detailed objects and advantages of the invention such as arise in connection with carrying out the above noted ideas in a practical embodiment will in part become apparent, and in part be hereinafter stated as the description of the invention proceeds.

The invention, therefore, comprises a combination stool and carrier consisting essentially of leg structure including front and rear legs, with the rear legs being provided with wheels at the lower free ends, and the front legs with step elements, constituting the front legs a step ladder. The leg structure supports a hingedly mounted seat providing access to a storage receptacle located therebeneath. The rear legs also support a back rest which is adapted for use as a handle when the stool is to be moved about.

For a full and more complete understanding of the invention, reference may be had to the following description and accompanying drawing wherein:

Figure 1 is a view in side elevation, with parts broken away of a stool designed in accordance with precepts of this invention;

Figure 2 is a view in front elevation, with parts broken away of the stool shown in Figure 1; and

Figure 3 is a detailed elevation taken about on the plane represented by the line 3—3 of Figure 1.

Referring now to the drawing, wherein like reference characters denote corresponding parts, and first more particularly to Figure 1, the stool 40 of this invention is shown as including a pair of front legs 10 and a pair of rear legs 11. Each of the legs 10 and 11 includes a main body portion that is straight and which assumes a vertical position when the stool is in its normal position. Each of these legs also includes a lower, outwardly-directed curve portion, with these portions of the several legs cooperating to provide what is in effect a wide base. The lower curved portions of the front legs 10 are designated 12 and the curved portion of the rear legs 11 are indicated as 13.

Extending between the lower portions 13 of the rear legs 11 is an axle or shaft 14 and journaled on this shaft 14 are a pair of small wheels or rollers 15. This arrangement is to be taken as

illustrative of one way in which wheels or rollers might be mounted on the lower ends of the rear legs 11. It is not intended as a limitation on the invention, because there are obviously other ways in which these wheels might be mounted.

At this point it is well to note that the leg structure, horizontal supporting braces and back rest are illustrated and described as made from metallic tubing, such as stainless steel tubing. This material is now meeting with wide-spread use in the field of kitchen furniture and is taken as illustrative of the preferred material from which these elements of the stool might be made. Obviously, other materials might be used without departing from the spirit of the invention.

Encompassing the legs 10 and 11, where the curved lower portions merge in with the straight main body portions is a lower horizontal support or brace 16. At the top of the legs 10 there is an upper horizontal support or brace 17 and encompassing the straight portions of the legs 10 and 11 and substantially midway the extremities thereof is an intermediate support or brace 18. The braces 16, 17 and 18 may be secured to the leg structure in any preferred manner, such as by being soldered or welded thereto.

A back rest is referred to in its entirety by the reference character B and comprises a piece of tubing that is bent into U formation, providing sides 19 and 20, the lower end portions of which are joined to the legs 11 at the upper ends thereof.

The aforementioned union may be effected in any preferred manner, such as by soldering or welding.

A seat is referred to in its entirety by the reference character S. It comprises a fixed bar-like portion 21 which is permanently secured in a fixed position across the upper ends of the rear legs 11 and a movable main body portion 22 which is hingedly connected to the fixed bar 21 by the hinge shown at 23.

The space beneath the seat S is enclosed by wall structure which may be made from any preferred material, such as thin plywood, plastic or sheet metal. This wall structure consists essentially of a front wall such as shown at 24, a rear wall 25 and a pair of side walls 26. These walls extend from the top brace 17 to the lower brace 16. A bottom for the storage space is provided by a bottom wall shown at 27.

In order to provide access to the storage space while a person is occupying the seat S, one of the side walls 26 is provided with a lower auxiliary door 28 which is hingedly mounted as indicated at 29 and provided with a handle 30 for manipulating purposes. Under ordinary conditions this door is kept closed, but it may be swung into an open position when access to the storage space is desired.

Immediately above the intermediate brace 18 the front wall 24 is deformed to provide an inwardly extending recess 31 and a horizontal shoulder 32. A step element 33 is supported on this shoulder 32 and the brace 18. The recess 31 accommodates the front portion of the user's foot when this step 33 is used as an element of the step ladder. In a similar manner, the wall 24 is deformed immediately above the lower brace 16 to accommodate a second step element 34 and provide an inwardly extending recess immediately thereabove to accommodate the toe of the user's foot.

Operation

While the manner of using the stool above de-

scribed is believed to be obvious from the description of the parts given, it may be briefly summed up as follows:

Under ordinary conditions the stool is supported in a customary manner by the lower portions 12 of the front legs 10 and wheels 15 carried by the rear legs 11. In this position a person may occupy the seat S and be seated in a comfortable manner against the back rest B.

When it is desired to use the storage space beneath the seat S to store articles, the seat S is raised by swinging it on the hinge 23 and the articles are deposited in the storage space. If desired, the auxiliary door 28 may be swung open for the same purpose.

When it is desired to use the stool as a carrier so as to move articles that are placed in the storage space, the user simply grasps the back rest B and tilts the stool backwardly so that the only support is provided by the wheels 15. The stool may now be pushed about much in the manner of a wheelbarrow or two-wheel pushcart.

When a step ladder is required, the stool is moved to the desired locality in the manner above prescribed and the step elements 33 and 34 are used in the same manner as the steps of a step ladder. In this connection it is notable that the wide base afforded by the curved portions 12 and 13 of the legs insures of adequate stability when the stool is used as a step ladder.

While a preferred specific embodiment of the invention is hereinbefore set forth, it is to be clearly understood that the invention is not to be limited to the exact constructions, mechanisms, and materials illustrated and described, because various modifications of these details may be provided in putting the invention into practice within the purview of the appended claims.

What is claimed is:

1. In a combination stool of the character described, leg structure including a pair of front legs and a pair of rear legs, a storage receptacle carried by said leg structure, including a bottom, front, rear and side walls, a seat hingedly mounted at the top of said rear wall and constituting a closure for the top of said storage receptacle, a pair of wheel elements at the lower end of said rear legs, and a back rest secured to the upper ends of said rear legs and adapted to function as a handle in cooperation with said wheels.

2. In a combination stool of the character described, leg structure including a pair of front legs and a pair of rear legs which extend from the top to the bottom of the stool, a storage receptacle carried by said leg structure, including a bottom, front, rear and side walls, a seat hingedly mounted at the top of said rear wall and constituting a closure for the top of said storage receptacle, and an auxiliary door hingedly mounted in the lower portion of one of the side walls of said storage receptacle.

3. In a combination stool of the character described, leg structure including a pair of front legs and a pair of rear legs which extend from the top to the bottom of the stool, a storage receptacle carried by said leg structure, including a bottom, front, rear and side walls, a seat hingedly mounted at the top of said rear wall and constituting a closure for the top of said storage receptacle, and a pair of step elements carried by said front legs at the front wall of said receptacle.

4. In a combination stool of the character de-

scribed, leg structure including front and rear legs, with the lower ends of said legs disposed outwardly as compared to the upper ends providing in effect a wide base, upper and lower horizontal braces carried by said leg structure, a storage receptacle disposed between said braces and including a bottom supported by said lower brace, a hingedly mounted seat secured to said rear legs above said upper brace, and step elements carried by said front legs.

5. In a combination stool of the character described, leg structure including front and rear legs, with the lower ends of said legs disposed outwardly as compared to the upper ends providing in effect a wide base, upper and lower horizontal braces carried by said leg structure, a storage receptacle disposed between said braces and including a bottom supported by said lower brace, a hingedly mounted seat secured to said rear legs above said upper brace, a pair of wheels at the lower ends of said rear legs, a back rest at the upper ends of said rear legs, and a pair of step elements carried by said front legs.

6. In a combination stool of the character described, leg structure including a pair of front legs and a pair of rear legs with the lower ends of said legs disposed outwardly as compared to the upper ends providing in effect a wide base, upper, lower, and intermediate horizontal braces secured to said legs, a storage receptacle defined

10
15

by front, rear, and side walls extending between said upper and lower braces, the front wall of said receptacle being deformed to provide an inwardly extending recess immediately above said lower and intermediate braces, step elements in

said front wall supported by said intermediate and lower braces, a seat hingedly mounted at the upper ends of rear legs above said upper

brace, one of the said side walls being provided with an auxiliary door immediately above said lower brace, a pair of wheels at the lower ends of said rear legs, and a U-shaped back rest secured to the upper ends of said rear legs.
